2,370,715

RAILROAD TIE

James B. Carmichael, Seattle, Wash.

Application August 24, 1943, Serial No. 499,796

2 Claims. (Cl. 238—79)

The present invention relates to the art of railroad ties and in more particular to the art of fabricated ties as compared to the natural wood tie.

In the prior art there have been several fabricated ties using various materials or combinations of materials. In all of these prior art devices there has been present the problem of designing a fastening means for quickly, simply, permanently, and firmly fastening the rail and tie together. Unless the fastening means is operable quickly, the cost of installing the ties will be excessive. If the fastening means is not simple, the unskilled workmen usually employed for this work will not be able to do the job. The fastening means must not be subject to rapid deterioration, but when once installed it must last for twenty to thirty years without service. If the track is not securely held to the tie, the resulting relative movement will allow creep in the track and excessive wear of the tie with a great reduction in the life thereof.

While it is desirable to have a heavy tie in order to have a solid bed, it is important that this weight be distributed over as large an area as possible so as to prevent the tie from sinking into the road-bed.

Having in mind these defects of the prior art, it is an object of the present invention to devise a fabricated railroad tie that has combined therewith a rail securing means that is simple and easy to operate, and which will permanently and firmly tie the rail and tie together.

Another object of the present invention is to construct a tie securing means which will draw the tie and rail together by a simple wedging means.

A further object of the invention is the provision of a tie anchor plate that may be secured to a tie by means of a simple drift pin.

Yet another object of the present invention is the provision of an anchor plate and locking arrangement that will tighten the rail to the tie.

Still another object of the present invention is the provision of a hollow tie that will provide a wide bearing surface for the tie.

A still further object of the present invention is the provision of a concave bearing face for the tie which allows the tie to compact the bed upon which it rests.

The above mentioned defects of the prior art and others are remedied or ameliorated, and the enumerated objects and others that will be apparent from the hereinafter description are at-

tained by means of the device shown in the accompanying drawing, in which:

Figure 1 is a perspective view of a tie embodying my invention, and in conjunction with a standard railroad rail,

Figure 2 is partial longitudinal section view of the tie shown in Figure 1 and is taken on the line 2—2 of Figure 3,

Figure 3 is a transverse sectional view of central portion of the tie and is taken on the line 3—3 of Figure 1,

Figure 4 is a sectional view on line 4—4 of Figure 2,

Figure 5 is a view illustrating the method of attaching an anchor plate to a rail,

Figure 6 is a perspective view of an anchor plate used in the present invention, and

Figure 7 is a perspective view of a cover plate which is associated with the tie of the present invention and which is used for closing the end openings of the tie.

In the views of the drawing there is shown a tie 1 which is preferably made of cast steel or cast alloy steel that is rust proof or rust resistant. The tie 1 is a hollow elongated frustum having the bottom, or bearing, surface 2 concave. The open ends 3, 4 of the tie are sloped outwardly so that when closed by a cover 5 such cover will naturally stay closed without the use of special securing means. The ends of the tie are provided on their upper portions with loops 9 forming slots 6, 7 into which the upper flanged end 8 of the cover 5 is adapted to be inserted. These slots and loops then serve as hinges and retainers for the cover, in cooperation with the flange 8 of the cover.

The upper face of the tie adjacent each end is provided with rail bearing surfaces 10, 11. Each such surface takes the place of the usual tie-plate and, like the tie plate, is provided with guide ribs 12, 13, and 14, 15 for preventing side movement of the rail relative to the tie.

Longitudinal movement of the rail is restricted and rising movement prevented by means of the anchor plates 16. Each anchor plate is provided at one end with two hooks 17, 18 that are arranged at opposite corners with the open part of each hook opposed to the open part of the other. These hooks and their shanks are so proportioned and spaced apart that when one hook is arranged over one flange of a rail as shown in Figure 5 the other hook may be swung above the other flange of the rail and then both hooks seated on their respective rail flange. Secured to each plate 55 is a locking pin 19 that is adapted to fit in a

hole 20 in the side of the tie. The free end of this pin has a slot 21 to receive a drift pin 22. Driving of the drift pin into the slot is possible because of the open end of the tie, particularly due to the slant to the open end. It is also to be noted that the slot of the pin is slanted with respect to the horizontal so that a worker standing above the tie may swing a maul down upon the head of the pin. One of these plates is arranged on each side of each end of the tie, making four anchor plates in all on each tie.

That portion of the tie against which each of the anchor plates rests has a concave face 23 with the curvature in the vertical plane. These anchor plate seats 23 have their vertical sides bounded by ribs 24, 25 that aid in preventing shifting of the anchor plates and the rails with respect to the tie.

In the use and operation of the above described device, the fabricated steel tie may be laid in the usual road bed in the same manner as present employed. The concave bottom surface will, under loading, compact the bed therebelow and the tie will not sink or shift as much as will a square sectioned wooden tie. In placing the tie, the end covers 5 may or may not be attached. When the tie is in place, the rails are laid on the bearing surfaces 10, 11, the anchor plates 16 hooked on the bottom flanges of each rail by placing first one and then the other of the hooks 17, 18 over a rail flange. The anchor plate pins 19 are then placed in the openings 20 and a drift pin 22 is inserted into the slot 21 in each locking pin. These drift pins are then driven tight in the slots. These locking pins, their slots,

and the drift pins are so proportioned that as the drift pins are driven home, the anchor plate will be bent to conform to the curvature of the anchor plate seats 23. This bending and drawing down of the anchor plate into its seat draws the ears 17, 18 down upon the rail flanges and securely seats the rail on the tie and prevents relative movement therebetween.

From the above description of my invention 10 and its operation and use, it is believed that its construction, operation and many advantages will be clearly understood.

Having thus described my invention, I claim:

1. A railroad tie having a tubular cross section, and locking means comprising an anchor plate adapted to be secured to a rail, a locking pin attached to said plate extending through an opening formed in a side of said tie, a drift pin fitting in a slot in said locking pin and bearing against the inside of said tie for tightening and securing said plate to said tie, and a concave depression in the side of said tie into which said anchor plate is forced by said drift pin for tightening the rail against said tie.

2. A railroad tie having a vertically concave depression on the side of the tie immediately below that point on the upper tie surface where a rail is placed, an anchor plate adapted to be secured to such positioned rail and to lie alongside said concave surface, and means for drawing said anchor plate securely against said concave surface to spring the anchor plate and to thus tighten the rail to the tie.

JAMES B. CARMICHAEL.
